FIG. 1.

FIG. 2.

FIG. 3.

STATE S. L. LEBBY,

By Howard E. Bleau
Attorney

UNITED STATES PATENT OFFICE.

STATES LEE LEBBY, OF CHARLESTON, SOUTH CAROLINA.

NO-GLARE HEADLIGHT.

1,327,563.

Specification of Letters Patent.

Patented Jan. 6, 1920.

Application filed November 20, 1917. Serial No. 202,926.

To all whom it may concern:

Be it known that I, STATES LEE LEBBY, a citizen of the United States, residing at Charleston, in the county of Charleston and

5 State of South Carolina, have invented certain new and useful Improvements in No-Glare Headlights, of which the following is a specification, reference being had thereto in the accompanying drawing.

10 My invention relates to lights for vehicles and especially to headlights such as are used upon automobiles. It has for its object to provide means to intercept the high light from the light source of a headlight 15 and deflect it onto the road bed, without permitting the rays to go above the horizontal plane of the lamp. An ancillary object is to cause a spreading illumination near the car for maneuvering in close places as well 20 as straight road driving.

In order to attain my objects, I provide a flat or plane reflector and light screen inserted in the headlight above and in front of the lamp, with a drop flange on the front 25 which projects downwardly to a central point below the axis of the lamp and filament.

My invention is illustrated in the accompanying drawings in which—

30 Figure 1 is a vertical longitudinal section,

Fig. 2 is a horizontal section on the line 2—2 of Fig. 1, and

35 Fig. 3 is a front view showing the shape of the screen flange.

Referring to the drawings in detail, 1 indicates the lamp casing in which is mounted a shallow parabolic reflector 2. A lamp socket 3 is mounted at the rear portion of 40 the lamp casing which may be arranged for longitudinal adjustment therein along the axis of the reflector. An electric lamp 4 having a concentrated filament 5 is carried by the socket 3 and in such adjustment with 45 relation to the reflector that the filament is positioned approximately at the focal point. A suitable cover 6 is provided for the front of the lamp casing and carries a plane glass pane or window 7.

50 Within the lamp casing and above and in front of the lamp 4, is mounted my improved light modifier 8 which is in the form of a combined reflector and screen extending horizontally across the lamp casing. The

top portion 9 of the light modifier is in the 55 form of a rectangle, as shown in Fig. 2, extending from side to side of the lamp casing and from a point a little in advance of the focus of the reflector to the front of the lamp substantially parallel to the axis of the 60 reflector, thus partitioning off the upper front portion of the lamp casing. The lower surface of the portion 9 is a plane reflector. The front portion 10 of the light modifier is bent to form a downwardly extending vertical flange projecting slightly below the horizontal axis of the lamp and tapering upwardly and outwardly from the center toward the sides of the lamp as indicated in Fig. 3. This front portion 10 70 forms a screen for cutting off the direct axial rays from the lamp and to regulate the light cast downwardly and to either side from the main reflector 2 and the horizontal reflector 9. As shown in Fig. 3, I form 75 the front screen flange 10 with an arc-shaped drop 11 at the center of its lower edge from which the oblique edges 12 extend upwardly to the sides of the lamp. This peculiar shape of the screen operates to reduce the 80 central or axial head-on glare while permitting the laterally diverging rays from both the light and the reflectors to pass out undiminished according to the point at which they pass out under the oblique edges of 85 the screen. It is to be noted that by placing the reflecting portion 9 of the light modifier in a horizontal plane, that is parallel to the head-on beam, the effectiveness of the light for straight ahead driving is sub- 90 stantially undiminished, while the upwardly directed rays from the light source which are usually of minor effectiveness, are utilized for illuminating the sides and bed of the road which is of great utility for maneuvering in close places.

Having thus described my invention what I claim and desire to secure by Letters Patent is—

1. A no-glare headlight comprising in 100 combination a casing containing a reflector, a lamp in the axis of said reflector, and a plane auxiliary reflector and screen having an extended flat body supported horizontally above the axis of the lamp in front of 105 the main reflector, and a drop flange on the front edge of said body having its central portion extending downwardly to a point

below the axis of the lamp so as to shield the same, and with its lower edges extending obliquely upward in both directions so as to permit a wide dispersion of the light rays.

2. A no-glare light screen for headlights and projectors comprising a flat horizontal

body and a drop flange relatively deep in the center and tapering off both ways to permit wide dispersion of the light rays. 10

In testimony whereof I affix my signature.

STATE LEE LEBBY.
